Patented Apr. 24, 1928.

UNITED STATES PATENT OFFICE.

EDWARD H. KLEINFELDT, OF NEW YORK, N. Y.

WALL CONSTRUCTION.

Application filed March 30, 1927. Serial No. 179,574.

This invention relates to wall structures and has particular reference to the building blocks or elements which make up the wall, the same being in the nature of an improvement over my prior United States Letters Patent No. 1,362,327, granted December 14, 1920.

The invention comprehends for one of its principal objects an improved means for defining an air circulation space within the wall to insulate the same against heat, cold and dampness, and to provide where desired a space for the circulation of heat through the wall to act as a conductor for conveying the heat throughout the building.

Other objects reside in the provision of means for insuring a proper alinement of the outer and inner surfaces of the blocks without depending upon the skill of the mechanic erecting the wall.

As a still further object the invention comprehends a wall structure including building blocks which are so constructed as to properly receive and accommodate the bonding material while concealing the same on the exterior surface of the wall.

Other objects reside in the comparative simplicity of construction, the economy with which the blocks or elements may be produced and the wall erected, and the general efficiency derived therefrom.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a perspective view of a portion of a wall constructed in accordance with the invention;

Fig. 2 is a vertical sectional transverse view therethrough;

Fig. 3 is an inverted perspective view of one of the building blocks or elements;

Fig. 4 is a plan view of a portion of the wall;

Fig. 5 is a vertical longitudinal sectional view taken approximately on the line 5—5 of Fig. 4;

Fig. 6 is a similar sectional view taken approximately on the line indicated at 6—6 in Fig. 4.

Referring to the drawings by characters of reference, 10 designates the intermediate blocks and 11 the corner blocks which embody the same general characteristics. The blocks 10 each consist of a pair of laterally spaced portions 12 and 13 which are joined by integral webs 14 and which spacing together with one of the webs, defines at one end a vertical groove 15, the opposite end being provided with a vertical tongue 16, the tongue 16 of one block being adapted to fit within the groove 15 of an adjacent block. 70 The tongues 16 are provided with beveled corners 17, which facilitates the engagement of the same within the grooves 15. Each block portion 12 and 13 is of substantially identical configuration and is formed on its 75 upper face with a longitudinally extending groove 18, while the under face is provided with a depending tongue 19 of less depth than the groove 18, the tongues 19 of one course of blocks being adapted to fit within 80 the grooves 18 of the next adjacent lower course. The tongues 19 are also provided with beveled lower corners 20, whereby the same are of gradually decreasing width toward the lower free ends to facilitate the engagement of the tongues in the grooves, 85 the remaining upper portion of the tongues, however, being of substantially the same width as the width of the grooves whereby said upper side edges snugly engaging with in the grooves, insures the proper alinement 90 of the faces of one course of blocks with the faces of the next adjacent upper and lower courses.

The bonding material 21 is placed in the 95 grooves 18 and the excess or residue is permitted to flow from the opposite ends of the grooves. The opposite ends of each portion 12 and 13 is formed with a substantially concave depression 22 extending vertically, 100 which affords a receiving space 23 for the bonding material while the remaining end surfaces 24 are directly engageable, thereby concealing from view the bonding material 105 when the wall is completed.

It will be noted that the space 25 between the block portions 13 allows for the circulation of air by forming a dead air space, or, if desired, suitable conduits may lead therethrough and outlets therefrom to permit of 110

the circulation of heat through the spaces 25 to act as a conductor for heated air in heating the building.

From the foregoing it will be seen that a 5 wall structure has been devised, which insures surface alinement of the blocks or elements without depending upon the skill of the mechanic erecting the building; that the bonding material while effectually connecting the blocks or elements, is concealed 10 from view, thereby presenting a neater appearance, and that a wall has been devised having an air circulation space therethrough to act as a conduit for a heating agent or as 15 a dead air space for insulating the building against dampness or external temperatures.

What is claimed is:

1. A wall construction including a plurality of courses of building blocks, each comprising laterally spaced portions joined by integral webs and defining air circulation spaces between the portions, the said blocks each having a vertical tongue at one end and a vertical groove at the opposite end for interengagement with similar elements formed on adjacent blocks, the end faces of each block portion having a substantially concave vertical recess, the side edges of which recess are spaced from the outer side faces of the 30 block whereby bonding material received in the recesses between two adjacent blocks is concealed from view.

2. A wall construction including a plurality of courses of building blocks, each comprising laterally spaced portions joined by integral webs and defining air circulation spaces between the portions, the said blocks each having a vertical tongue at one end and a vertical groove at the opposite end for interengagement with similar elements formed on adjacent blocks, the upper face of each block portion having a longitudinal groove for the reception of a bonding material and the lower face of each block portion having a longitudinal tongue of lesser depth than the groove to afford a space for accommodating the bonding material, the said tongues and grooves of adjacent superimposed blocks adapted to interfit.

3. A wall construction including a plurality of courses of building blocks, each comprising laterally spaced portions joined by integral webs and defining air circulation spaces between the portions, the said blocks each having a vertical tongue at one end and a vertical groove at the opposite end for interengagement with similar elements formed on adjacent blocks, the upper face of each block portion having a longitudinal groove for the reception of a bonding material and the lower face of each block portion having a longitudinal tongue of lesser depth than the groove to afford a space for accommodating the bonding material, the said

tongues and grooves of adjacent superimposed blocks adapted to interfit, the upper portion of the tongues being of a size to snugly fit the grooves for insuring proper alinement of the outer surfaces of the blocks.

4. A wall construction including a plural- 70 ity of courses of building blocks, each comprising laterally spaced portions joined by integral webs and defining air circulation spaces between the portions, the said blocks each having a vertical tongue at one end and 75 a vertical groove at the opposite end for interengagement with similar elements formed on adjacent blocks, the upper face of each block portion having a longitudinal groove for the reception of a bonding material and the 80 lower face of each block portion having a longitudinal tongue of lesser depth than the groove to afford a space for accommodating the bonding material, the said tongues and grooves of adjacent superimposed blocks 85 adapted to interfit, the upper portion of the tongues being of a size to snugly fit the grooves for insuring proper alinement of the outer surfaces of the blocks, and the lower portion of the tongues being of gradually 90 decreasing widths toward their lower free ends to facilitate their engagement with the grooves.

5. A building block for wall construction, comprising laterally spaced block portions joined by an integral web and defining when associated with similar blocks, air circulation spaces between the block portions, the said blocks each having at one end a vertical centrally disposed tongue and at the opposite end a vertical centrally disposed groove, the end faces of each block portion between the groove or tongue and outer side surfaces having a recess for the reception of a bonding material, which end faces when in contact with adjacent blocks conceal the binding material from view.

6. A building block for wall construction, comprising laterally spaced block portions joined by an integral web and defining when 110 associated with similar blocks, air circulation spaces between the block portions, the said blocks each having at one end a vertical centrally disposed tongue and at the opposite end a vertical centrally disposed groove, 115 the end faces of each block portion between the groove or tongue and outer side surfaces having a recess for the reception of a bonding material, which end faces when in contact with adjacent blocks conceal the binding 120 material from view, and the upper faces of each block portion having a longitudinal groove for the reception of a binding material and the lower faces of each block portion having a longitudinal tongue of less 125 depth than the groove.
